COKE OVEN MACHINE

Charles E. Underwood, Bethlehem, Pa., assignor
to Bethlehem Steel Company, a corporation of
Pennsylvania

Application April 2, 1932, Serial No. 602,662

19 Claims. (Cl. 214—23)

My invention relates to the general arrangement of a machine for use in connection with retort by-product coke ovens and more especially to the manner of mounting the mechanism 5 on a single carriage for removing and replacing the doors on the pusher side of the oven, ejecting the coke from the ovens, sealing the space around the doors after replacement and then leveling the coal after it has been charged into 10 the oven.

The present machines of this type in use at the coke oven plants of today are equipped with tools for performing the following operations:

A door manipulating mechanism for removing 15 and replacing the doors on the pusher side of the ovens.

A ram to push the coke out of the oven into the receiving car on the coke side of the ovens.

A leveling bar to level off the coal charged 20 into the oven through an opening usually in the top portion of the door or above the same.

A mud buggy is also sometimes installed on the carriage of the machine which is used for sealing the space around the door after the coke 25 has been ejected from the oven and the door replaced and before the oven is recharged with coal.

While thought and time have been expended to 30 improve the mechanical operation and durability of this equipment, its operations on account of the different tools being mounted in fixed spaced relation to each other usually take place one at a time, with the result that while the men working with this machine could easily do more work, their output is limited by the speed of 35 operation of the machine. This lost time consumed by the carriage in traveling or moving back and forth to place itself in position to use its various tools as needed to complete the cycle 40 of operation.

From time to time bituminous coal is charged 45 into one or more of the ovens of the battery while similar charges in other ovens are being coked. As the charges in various ovens forming a battery or a number of batteries are in different conditions, some of the coal being green, other ovens filled with coal that is partially coked, still others with coke that is practically 50 finished, this gives a fairly constant amount of distillate gas supply which is gathered in a collecting main from which point it is delivered to by-product recovering devices which separate the by-product from the gases, and a portion of 55 the gas is then finally returned to the battery.

for heating the same, while the excess gas is used for commercial purposes.

The finished charges of coke in the ovens are pushed in a coke plant in series of every fifth oven, tenth or some other combination that satisfies the management that the heat distribution through the battery of ovens is the best they can possibly obtain.

My machine is designed in such a manner that it can be built to meet the conditions of any 65 particular plant. For illustration the one shown in the drawings covers the construction for a five oven series but it will be readily understood that by varying the distance between the leveling bar and door manipulator and pusher ram any 70 pushing series may be obtained.

With my machine it is possible for the carriage to remain stationary while it completes four 75 operations after ejecting the coke from the first oven.

One of the objects of my invention is to mount horizontally side by side on a single carriage a combination of means which will make it possible to maintain the carriage in one position 80 in front of the battery at the same time allowing the pusher ram and door manipulator to be laterally adjusted in relation to the leveling bar.

Another object of my invention relates to the manner of mounting the door manipulator, pusher ram and leveling bar in spaced relation 85 in such a manner that two ovens can be operated on at the same time.

Another object of my invention relates to the manner of mounting the door manipulator and pusher ram on a pivoted platform in horizontal 90 radial alignment with the pivotal point which allows the outer end to be adjusted without moving the carriage.

Another object of my invention relates to the particular manner of mounting and operating 95 the leveling bar by gearing in such a way that the bar may be advanced or retracted by one mechanism with separate mechanism for giving the leveling bar a comparatively short reciprocating stroke.

Other objects will appear hereinafter.

Having given a general description of my invention I will now, in order to make the same more clear, refer to the accompanying two sheets 105 of drawings in which like characters refer to like parts.

Figure 1 is a top plan of my improved machine for handling the doors of coke ovens, ejecting the coke therefrom, leveling the charge therein and a mud box for sealing the doors, 110

with a portion of the battery shown in section; Fig. 2 is a side elevation of the machine shown in Fig. 1; and

Fig. 3 is a side elevation of the leveling bar mechanism taken on the line 3—3 of Fig. 1.

In the drawings which are shown more or less diagrammatically the numeral 1 indicates the carriage provided with rollers 2 journaled in bearings mounted on the girders 3 and adapted 10 to travel on the rails 4.

The axles 5 of two of the rollers 2 have gears 6 mounted thereon meshing with pinions 7 on the ends of a drive shaft 8, having a gear 9 mounted centrally thereon for meshing with a 15 pinion 10 on the shaft of a motor 11 for rotating the shaft for operating the carriage.

Secured on top of the carriage near the rear end at one side thereof is a center bearing plate 12 having a central perforation adapted to receive 20 the king bolt 13 extending from a bearing plate 14 secured to the under side of the pivoted platform 15 near the inner end, the forward and intermediate portion of the platform being supported on track segments 16 and 17 by means 25 of rollers 18 which are secured to the platform by means of brackets, the forward end of the pivoted platform being limited in its lateral movement by means of stops 19. Standards 20, 21, and 22 are mounted at spaced intervals on 30 the platform in which are mounted idler rollers 23 for guiding a pusher ram 24 which has a rack formed on its under side for meshing with a pinion 25 on shaft 26 journaled in the bearing 22, the outer end of said shaft being connected 35 by means of reduction gearing 27, driven by means of a motor 28. Mounted in the platform 15 laterally thereof at one side of the pusher ram 24, is a door manipulator 29, mounted in standards 30 and 31 between idler rollers 32 for 40 guiding the same. The under side of the shaft of said door manipulator has a rack formed thereon as at 33 meshing with a pinion 34, the shaft of which is journaled in standard 31 and connected with reduction gearing 35 and actuated 45 by means of a motor 36. The forward end of the door manipulator is formed with hooks 37 for engaging the lugs 38 on doors 39 for closing the pusher side of the coke ovens 40. In order to adjust or swing the outer end of 50 the platform 15 with the pusher ram 24 and the door manipulator 29 mounted therein, a motor 41 is mounted on the front end of the platform which is connected by means of gearing 42 to a rack 43 formed on the track segment 55 17.

A leveling bar 44 is mounted laterally of the pivoted platform on one side of the carriage 1, the forward end of the leveling bar being supported between standards 45 and idler rollers 60 46 while the rear end of the leveling bar is guided between posts 47 and idler rollers 48, mounted on a car 49 supported on wheels 50 engaging a track 51, said car having a motor 52 and reduction gearing 53 for bodily advancing 65 the car and the leveling bar. The motor 52 and gearing 53 connected therewith will advance the leveling bar slowly into the coke oven. When the leveling bar encounters a pile of coal which cannot be leveled by the slow movement 70 of the leveling bar into the oven the leveling bar can be given a short stroke reciprocating motion independent of the motor 52 by throwing in the motor 54 geared to crank arms 55 and pitmen 56 pivoted to a sector gear 57 journaled on the car body. This sector gear 57

engages gears 58 and has a gear 59 adapted to engage a rack 60 on the under side of the leveling bar.

A mud buggy or bucket 61 is pivoted by means of an arm 62 to a standard 63 which may be 80 swung out when desired for sealing the doors after they have been replaced before charging the ovens. An operator's cab 64 is mounted on the carriage in which the controllers (not shown) for operating the different motors may 85 be installed.

The operation of my invention is as follows: After the door of the first oven is removed by means of the door manipulator 29 and the platform 15 swung from the dotted position into the full line position indicated in Fig. 1 of the drawings the pusher ram 24 is then advanced into the oven the full length thereby ejecting the coke from the oven into a coke quenching car or the like receptacle on the opposite side of the battery, the pusher ram 24 is then returned to the position shown in the drawings and the platform swung into the dotted line position and the door replaced in the end of the oven, the carriage will then be advanced a 100 distance equal to five ovens until the leveling bar is properly centered for its operation, the luter man will then swing out his luter box, and start his operation of sealing the door, while he is swinging out his luter box and completing 105 his operation the movable platform 15 holding the pusher ram 24 and door manipulator 29 will swing into position, remove the door of the oven and swing the pusher ram into operating position. The operation of mudding the 110 previous door taken off, taking off the door of the next oven to be pushed and swinging the pusher ram into position for its work will be finished at the same time. The first oven discharged having been recharged with coal in 115 the usual manner, the control is then thrown in, starting the leveling bar into operation, this can be then left to itself while the operator pushes the coke from the oven, after the coke in the oven has been ejected and the pusher ram 120 retracted into its normal position, the door manipulating machine is operated to replace the oven door, the leveling operation has been completed and the carriage with the machines mounted thereon moves up another series of 125 five ovens to repeat the cycle.

Although I have described and illustrated my invention in considerable detail, I do not wish to be limited to the exact and specific details thereof, as shown and described, but may use 130 such modifications in substitutions for, or equivalents thereof, as are embraced within the scope of my invention, or as pointed out in the claims.

Having thus described my invention what I 135 claim as new and desire to secure by Letters Patent is:

1. In a machine of the character described, a carriage, a leveling bar mounted on the carriage, a platform pivoted to the carriage, means for adjusting laterally one end of the platform, a pusher ram mounted on the platform, and a door manipulating mechanism mounted 140 on the platform at one side of the pusher ram.

2. In a machine of the character described, 145 a carriage, a leveling bar movably mounted on the carriage at one side thereof, a platform pivoted near one end to the carriage, means for laterally adjusting the opposite end of the platform, door manipulating mechanism mounted 150

- on the adjustable end of the platform, and a pusher ram mounted on the platform in spaced relation to the door manipulating mechanism. 3. In a machine of the character described, 5 a carriage mounted to travel on a track, means for driving the carriage, a leveling bar mounted on the carriage at one side thereof, means for reciprocating the leveling bar transversely of the carriage, a platform pivoted near one 10 end to the carriage, door manipulating mechanism mounted on the platform, a pusher ram mounted on the platform in spaced relation to the door manipulating mechanism, and means for laterally adjusting the door manipulating mechanism and pusher ram in relation to the leveling bar. 15 4. In a machine of the character described, a carriage mounted to travel on a track, means for driving the carriage, a leveling bar mounted 20 on the carriage, means for guiding and supporting the front end of the leveling bar, means for guiding and supporting the rear end of the leveling bar, means for advancing and retracting the leveling bar, independent means for reciprocating the leveling bar, a platform pivoted near 25 one end to the carriage in horizontal spaced relation to the leveling bar, means for supporting and laterally adjusting the opposite end of the platform, door manipulating mechanism mounted on the platform in radial alignment with the pivotal point of the platform, means for advancing and retracting the door manipulating mechanism, a pusher ram mounted on the platform in lateral spaced relation with the door manipulating mechanism and in radial alignment with the pivotal point of the platform, and 30 means for reciprocating the pusher bar. 5. In a machine of the character described, a carriage mounted to travel on a track, means for driving the carriage, a leveling bar mounted 35 on the carriage at one side thereof, a platform pivoted near one end to the carriage, means for supporting and laterally adjusting the opposite end of the platform, door manipulating mechanism mounted on the platform, and a pusher ram 40 mounted on the platform in spaced relation to the door manipulating mechanism. 6. In a machine of the character described, a carriage mounted to travel on a track, means for driving the carriage, a leveling bar mounted 45 on the carriage, means for advancing and retracting the leveling bar, a platform pivoted near one end to the carriage in spaced relation to the leveling bar, means for supporting and laterally adjusting the opposite end of the platform, door manipulating mechanism mounted on the platform in radial alignment with the pivotal point of the platform, and means for reciprocating the door manipulating mechanism. 7. In a machine of the character described, a carriage mounted to travel on a track, means for driving the carriage, a leveling bar mounted 50 on the carriage, means for advancing and retracting the leveling bar, a platform pivoted near one end to the carriage in spaced relation to the leveling bar, means for supporting and laterally adjusting the opposite end of the platform, door manipulating mechanism mounted on the platform in radial alignment with the pivotal point of the platform, and means for advancing and retracting the pusher ram. 8. In a machine of the character described, a carriage mounted to travel on a track, means for driving the carriage, a leveling bar mounted 55 on the carriage, means mounted on the carriage for advancing and retracting the leveling bar, a platform pivoted near one end to the carriage in spaced lateral relation to the leveling bar, means for supporting and laterally adjusting the opposite end of the platform, door manipulating mechanism mounted on the platform in spaced relation to the door manipulating mechanism, means for advancing and retracting the door manipulating mechanism, a pusher ram mounted on the platform in lateral spaced relation with the door manipulating mechanism, and means for reciprocating the pusher ram. 9. In a machine of the character described, a carriage mounted to travel on a track, means for driving the carriage, a leveling bar mounted on the carriage having means thereon for advancing and retracting the leveling bar, a platform pivoted near one end to the carriage in horizontal spaced relation to the leveling bar, means for supporting and laterally adjusting the opposite end of the platform, door manipulating mechanism mounted on the platform in radial alignment with the pivotal point of the platform, means for advancing and retracting the door manipulating mechanism, a pusher ram mounted on the platform in lateral spaced relation with the door manipulating mechanism and in radial alignment with the pivotal point of the platform, and means for reciprocating the pusher bar. 10. The combination with a battery of coke ovens having a plurality of horizontal coking ovens with doors therefor, of a carriage horizontally movable longitudinally of the battery and transversely of the ovens, a leveling bar mounted on the carriage, means for advancing and retracting the leveling bar for leveling the charge in a coke oven, a platform pivoted near one of its ends to the carriage in horizontal spaced relation with the leveling bar, means for supporting the opposite end of the platform, door manipulating mechanism mounted on the platform, means for reciprocating the door manipulating mechanism, a pusher ram mounted on the platform in lateral spaced relation to the door manipulating mechanism, means for reciprocating the pusher ram, and means for laterally adjusting the door manipulating mechanism and pusher ram in relation to the leveling bar. 11. The combination with a battery of coke ovens having a plurality of horizontal coke ovens with doors therefor, of a carriage horizontally movable longitudinally of the battery and transversely of the ovens, a leveling bar mounted on the carriage for operating on one of the ovens, door manipulating mechanism and pusher ram mounted in horizontal spaced relation to the leveling bar for simultaneously operating on an oven in spaced relation to the oven being operated on by the leveling bar, and means for laterally adjusting the door manipulating mechanism and pusher ram in relation to the leveling bar. 12. The combination with a battery of coke ovens having a plurality of horizontal coke ovens with doors therefor, a carriage horizontally movable longitudinally of the battery and transversely of the ovens, a leveling bar mounted on the carriage, means for advancing the leveling bar into a coke oven, means for reciprocating the leveling bar independent of the means for advancing the leveling bar, a platform pivoted to the carriage in lateral spaced relation to the leveling bar, a door manipulating mechanism and pusher ram mounted on the pivoted platform for operating simultaneously on an oven in spaced relation to that operated upon by the leveling bar, and means for laterally adjusting the leveling bar.

the space between door manipulating mechanism and pusher ram and the leveling bar.

13. The combination with a battery of coke ovens having a plurality of horizontal coke ovens with doors therefor, a carriage horizontally movable longitudinally of the battery and transversely of the ovens, a leveling bar, means mounted on the carriage for supporting one end of the leveling bar, means mounted on the carriage for supporting the opposite end of the leveling bar, means for advancing or retracting the leveling bar for leveling a charge in a coke oven, independent means mounted on the carriage for reciprocating the leveling bar, a platform pivoted to the carriage in longitudinal spaced relation to the leveling bar, a door manipulating mechanism and pusher ram mounted in horizontal spaced relation to each other on the pivoted platform for operating on another oven simultaneously with the operation of the leveling bar, and means for adjusting the space between door manipulating mechanism and pusher ram and the leveling bar.

14. The combination with a battery of coke ovens having a plurality of horizontal coke ovens with doors therefor, a carriage horizontally movable longitudinally of the battery and transversely of the ovens, a reciprocating leveling bar mounted upon the carriage, a platform mounted on the carriage in horizontal spaced relation to the leveling bar having a pivoted end and a movable end adapted to travel in the arc of a circle around the pivoted end, rollers secured to the movable end of the platform, track segments for engaging the rollers for supporting the movable end of the platform, a rack formed on one of the segments, a motor having a gear connection with the rack for adjusting the movable end of the platform, a door manipulating mechanism mounted on the platform, a pusher ram mounted on the platform in horizontal alignment and in spaced relation to the door manipulating mechanism, means for advancing and retracting the door manipulating mechanism and means for reciprocating the pusher ram.

15. The combination with a battery of coke ovens having a plurality of horizontal coke ovens with doors therefor, a carriage horizontally movable longitudinally of the battery and transversely of the ovens, a leveling bar mounted on

the carriage, means mounted on the carriage adapted to travel with the leveling bar having independent means mounted thereon for reciprocating the leveling bar to level the charge in one of the coke ovens, a platform pivoted near one end to the carriage, means for laterally adjusting one end of the platform, and a pusher ram and door manipulating mechanism mounted in horizontal spaced relation to each other on the adjustable end of the platform.

80
85

16. The combination with a battery of coke ovens having a plurality of horizontal coke ovens with doors therefor, a carriage horizontally movable longitudinally of the battery and transversely of the ovens, a leveling bar mounted on the carriage, means mounted on the carriage for advancing and retracting the leveling bar, independent means for reciprocating the leveling bar adapted to level the charge in one of the coke ovens, a platform mounted laterally of the leveling bar and pivoted near one end to the carriage, means for supporting and laterally adjusting one end of the platform in relation to the leveling bar, a pusher ram and door manipulating mechanism mounted in horizontal spaced relation to each other on the adjustable end of the platform, means for reciprocating the pusher ram, and means for advancing and retracting the door manipulating mechanism.

90
95

17. In a machine of the character described, a carriage, a leveling bar on said carriage, a pusher element on said carriage in spaced relation to said leveling bar, and means mounted on the carriage and movable independently thereof to adjust the space between said pusher element and said leveling bar.

100
105

18. In a machine of the character described, a carriage, a leveling bar on said carriage, a pusher element on said carriage in side by side relation to said leveling bar, and means mounted on the carriage to laterally move said element toward and away from said leveling bar.

110
115

19. In a machine of the character described, a carriage, a longitudinally movable leveling bar on said carriage, a pusher element on said carriage independently mounted in lateral spaced relation to said leveling bar and adapted to rotate about a vertical axis, and means to cause said rotation.
